DESIGN FOR A SET OF NUMBERING HEAD DIGITS

Peter Aitchison, New Rochelle, N. Y., assignor to
American Bank Note Company, New York,
N. Y., a corporation of New York

Application May 9, 1935, Serial No. 56,763

Term of patent 14 years

To all whom it may concern:

Be it known that I, Peter Aitchison, a citizen of the United States, residing at New Rochelle, in the county of Westchester and State of New York, have invented a new, original, and ornamental Design for a Set of Numbering Head Digits, of which the following is a specification, reference being had to the accompanying drawing, forming a part thereof.

The drawing is a plan view of a set of digits forming the subject matter of my design. The set of digits is used upon a numbering head digit wheel.

I claim:

The ornamental design for a set of numbering head digits as shown in the accompanying drawing and described.

PETER AITCHISON.
